LUMINOUS ADVERTISING APPARATUS

Gordon W. Kent, Canton, Ohio

Application October 31, 1934, Serial No. 750,846

4 Claims. (Cl. 40—130)

My invention relates to advertising apparatus and the like of the general type in which light means are used to produce an image on a translucent screen which is intended to be viewed 5 from one side thereof.

Such advertising apparatus is very useful, particularly in connection with retail merchandising.

For such purposes, as well as for other forms 10 of advertising purposes, such as billboard advertising, it is very desirable to produce on a screen a luminous image which may be very large and which may be colored.

It is also very desirable to be able to change the image or copy from time to time with ease 15 and with low cost.

It is also very desirable to provide luminous advertising apparatus of the above character, and which is adapted for incorporation in a unitary box or case, and the parts of which are easily 20 manipulated.

Luminous advertising apparatus heretofore available do not have the characteristics, and are not operative, as above set forth.

The objects of the present improvements in- 25 clude the provision of a luminous advertising apparatus which has the characteristics, and which is operative, as above set forth.

Further objects of the present improvements include the provision of a luminous advertising 30 apparatus having the foregoing characteristics and which is adapted for easy and economical manufacture and use.

The foregoing and other objects are attained by the improvements, apparatus, parts, combinations, and sub-combinations, which comprise the present invention, and the nature of which is set forth in the following general statement, and preferred embodiments of which, together with their mode of use, are set forth in the following 40 description, and which are particularly and distinctly pointed out and set forth in the appended claims forming part hereof.

The nature of the improvements of the present invention may be described in general terms 45 as including preferably a unitary box or case having a translucent screen in one wall thereof which is adapted to be viewed from the outside by one or more observers.

For the purposes of best attaining the objects 50 of the present improvements, the translucent screen is preferably a single thickness opalite glass plate screen.

At the side of the translucent screen opposite to the viewed side thereof, that is to say, prefer- 55 ably within the box or case, a point source of

light is provided, and light intercepting means is interposed between the light source and the screen.

The light intercepting means may be a translucent glass plate or film painted in colors or otherwise with the desired copy or pictures, and means are provided for adjusting the location of the point source of light and the light intercepting means so that an enlarged image of the copy or pictures of the light intercepting means is projected upon the opalite glass screen, and may be viewed with clearness and distinction from the outside of the box or case. 5

Luminous advertising apparatus embodying the present improvements are illustrated in the 15 accompanying drawing forming part hereof, in which.

Figure 1 is a longitudinal sectional view of one embodiment of the improved luminous advertising apparatus as on lines 1—1, Figs. 2 and 3; 20

Fig. 2, a transverse sectional view thereof as on line 2—2, Fig. 1;

Fig. 3, a front end view thereof, looking at the observer's side of the opalite glass screen;

Fig. 4, a fragmentary plan view of the interior 25 portions of the preferred box or case and its contents, looking in the direction of the arrows 4—4, and illustrating the construction and arrangement of the point source of light and the light intercepting means and the adjustable mounting means therefor; and

Fig. 5, a fragmentary view similar to Fig. 1, 30 illustrating a modified form of the improved apparatus.

Similar numerals refer to similar parts 35 throughout the several views.

One embodiment of the improved luminous advertising apparatus is illustrated in Figs. 1 to 4 inclusive and is indicated generally by 10, and preferably includes a unitary box or case 11 having in one side or end wall thereof a translucent screen member 12 which is preferably a single thickness opalite glass plate screen, opalite glass having at least on one surface thereof a fused lamina of white translucent material, and the single thickness opalite glass plate being substantially 0.06 inch thick. 40

Double thickness opalite glass plate is not operative for the purpose of the present improvements in the same manner as the preferred single 45 thickness glass plate.

The outer face or side 13 of the preferred opalite glass plate screen 12 is adapted to be viewed by one or more observers.

The box 11 furthermore includes a bottom wall 50

14, a side or end wall 15 opposite the screen member 12, opposite spaced side walls 16 and 17 and a top wall 18. One of the side walls, as illustrated the side wall 17 is preferably formed in 5 part by an upwardly opening door 19 through the opening of which access to the interior compartment 20 of the box or case 11 is effected.

Within the compartment 20 of the unitary case 11, a point or spot source of light indicated generally by 21 is provided and between the point source of light 21 and the screen 12, light intercepting means indicated generally by 22 are located.

The point source of light 21 is preferably provided with means indicated generally by 23 for adjusting its distance from the screen means 12; and means indicated generally by 24 are provided for adjusting the position of the light intercepting means 22 with respect to the screen means 12 20 and the light source 21.

As illustrated the point source of light 21 is provided by an electric flash light lamp 25 which has a filament 25' providing a point or spot of light of relatively high intensity.

25 The flash light lamp 25 may be operated by batteries or by a transformer which derives its power from a usual electric light circuit.

The adjusting means 23 for the point source of light 21 as illustrated, includes a slidable block 30 26 on which a base receptacle 27 is secured, and the lamp 25 is screwed in the receptacle 27 in a usual manner.

Between the block 26 and the wall 15 a mounting block 28 is secured to the bottom wall 14 35 of the case 11, and a rod 29 slidably extends through a bore provided in the block 28, and one end 30 of the rod 29 is secured to the block 26.

Thumb-screw means 31 are operatively mounted in the block 28, whereby the position of the block 26 with respect to the position of the screen 12 and thus of the filament 25' or the point source of light 21 may be releasably adjusted, by releasing the thumb screw means 31 and sliding the rod 29 back and forth through the block 28. 45 The block 26 being secured to the end 30 of the rod 29, moves with the rod 29, and may be grasped directly in adjusting its position.

After the desired position of the point source of light has been attained, the thumb screw means 31 are tightened and the point source of light 21 is maintained at the desired position.

As illustrated, the means 24 for adjusting the position of the light intercepting means 22 with respect to the point source of light 21 and the screen 12, includes a grooved base 32 which is pivotally mounted on one end of a swinging frame 33, the other end of which is pivotally mounted on the block 28. The pivotal mounting means for each end of the frame 33 may be 60 as illustrated bolt and thumb nut means indicated generally by 34.

The block 32 is located between the point source of light 21 and the screen 12 and as illustrated has a transverse groove 35 formed therein in 65 which is seated the light intercepting means 22, which as illustrated is a glass plate 36 having the words "Dollar day" painted thereon.

When the lamp 25 is illuminated, the operation of the improved apparatus 10 is to produce an enlarged image of the words "Dollar day" or such other black, or colored copy or design as may be applied to or formed by the light intercepting means 22, on the screen 12, the enlarged image being clearly and distinctly visible by one 70 or more observers as shown in Fig. 3.

In the modified embodiment of the improvements illustrated in Fig. 5 and indicated generally by 110, the apparatus is generally similar to the apparatus 10, but includes a high voltage lamp 125 provided with a shield tube 137 which has a small aperture 138 formed therein opposite the light intercepting means 122, whereby the shield tube 137 in combination with the high voltage lamp 125 provides a point or spot source of light. 5

I claim:

1. Unitary optical apparatus for advertising and the like, including a case, one wall of the case having a screen opening, a translucent screen member in the screen opening, another wall of the case having an access opening adapted to be closed, a point source of high intensity light within the case, adjustable means within the case operatively mounting the light source for movement towards and away from the screen, and adjustable means within the case adapted for holding a light intercepting member, the adjustable holding means including a base located between the light source and the screen, and swinging frame means pivotally mounting the base for movement between the light source and the screen. 25

2. Unitary optical apparatus for advertising and the like, including a case, one wall of the case having a screen opening, a translucent screen member in the screen opening, another 30 wall of the case having an access opening, a door for the access opening, a point source of high intensity light within the case, adjustable means within the case operatively mounting the light source for movement towards and away from the screen, and adjustable means within the case adapted for holding a light intercepting member, the adjustable holding means including a base located between the light source and the screen, and swinging frame means pivotally mounting the base for movement between the light source and the screen. 35

3. Unitary optical apparatus for advertising and the like, including a case, one wall of the case having a screen opening, a translucent screen member in the screen opening, another wall of the case having an access opening adapted to be closed, a point source of high intensity light within the case, adjustable means within the case operatively mounting the light source for movement towards and away from the screen, and adjustable means within the case adapted for holding a light intercepting member, the adjustable holding means including a grooved base located between the light source and the screen, and swinging frame means pivotally mounting the base for movement between the light source and the screen. 40

4. Unitary optical apparatus for advertising and the like, including a case, one wall of the case having a screen opening, a translucent screen member in the screen opening, another wall of the case having an access opening, a door for the access opening, a point source of high intensity light within the case, adjustable means within the case operatively mounting the light source for movement towards and away from the screen, and adjustable means within the case adapted for holding a light intercepting member, the adjustable holding means including a grooved base located between the light source and the screen, and swinging frame means pivotally mounting the base for movement between the light source and the screen. 50
